ADJUSTABLE SEAT SUPPORT

Filed Jan. 17, 1935

Fig. 1

Fig. 2

Fig. 3

Fig. 6

Figures 4 and 5 illustrate a cylindrical device, likely a filter or a component of a medical instrument. Figure 4 shows a cross-sectional view of the device, revealing a central tube 41 with a ribbed outer surface. A flange 40 is attached to the top of the tube, and a support structure 44 is shown. Figure 5 shows a side view of the device, highlighting its ribbed outer surface and a central tube 41. The device is labeled with reference numerals 40, 41, 42, 44, and 46.

ADJUSTABLE SEAT SUPPORT

Walter S. Saunders, Pontiac, Mich., assignor to
The American Forging and Socket Company,
Pontiac, Mich., a corporation of Michigan

Application January 17, 1935, Serial No. 2,248

2 Claims. (Cl. 155—14)

This invention relates to adjustable seat supporting devices, and is particularly applicable to vehicle seats, as those used in automobiles, which are desired to be adjustable in position by persons sitting in them, with a minimum of effort and without requiring such persons to rise from the seat. An important object of the invention is the provision of improved and simplified seat adjusting mechanism of great strength and reliability of operation and extremely simple and inexpensive construction, formed almost entirely of stamped sheet metal and provided with novel and simplified latching means easily operable by an occupant of the seat.

Another object of the invention is the provision of improved adjustable seat supporting means which when used in conjunction with a relatively long seat, such as those commonly provided in sedan type automobile bodies, enables easy sliding of the seat to desired positions, by force applied at either end, without the possibility of thereby moving one end faster and farther than the other and so cocking or turning the seat to a position in which it jams with respect to its guiding means, and its free movement or the operation of the latching means is interfered with. Such cocking and jamming of the seat has been found to constitute a frequent source of difficulty with adjustable seat supports as commonly constructed. In conjunction with this last mentioned object I aim also to provide novel means for positively transferring the driving force from one end of such a seat to the other, so that no matter which end (or other portion) of the seat is pushed or pulled to move it, the entire seat is made to move with and at the same rate as the part to which the force is applied.

The provision of an improved and greatly simplified roller construction of novel design for providing efficient anti-friction bearing between relatively movable parts at very little cost is another object of this invention.

Other objects and advantages will be apparent from the following description wherein reference is made to the accompanying drawing illustrating preferred embodiments of my invention and wherein similar reference numerals designate similar parts throughout the several views.

50 In the drawing:

Figure 1 is a horizontal section partly in plan fragmentarily showing the interior and other portions of a sedan type automobile equipped with seats provided with adjusting means in accordance with the principles of this invention.

Figure 2 is a plan view of one of my adjustable supporting devices, fragmentarily showing the cross shaft by means of which it is preferably connected to another cooperating unit which may be of like construction.

Figure 3 is a vertical section taken substantially on the line 3—3 of Figure 1 and looking in the direction of the arrows and showing the adjustable supporting device in side elevation.

Figures 4 and 5 are side elevation and exploded perspective views respectively of one of my improved roller bearing units; and

Figure 6 is a fragmentary front elevational view of the device.

In the drawing, reference characters 10 and 11 designate supporting legs upon which the seat and adjusting mechanism are carried, the lower member of the latter comprising a flanged channel iron 12 constituting a track, and the cross-sectional contour of which is clearly shown in Figure 6. Another complementarily formed channel member 14, constituting a carriage, is inverted over and slidable relatively to the track channel and provided with a bight portion of similar size. The carriage channel is also provided with flanges 15 which are longer than the flanges 13 of the track channel. Carried by the flanges 15 are keying portions 16 which freely under-hang the shorter flanges of supporting track channel 12, thus permitting sliding movement of the carriage channel while preventing its vertical separation from the track channel.

Within the rectangular space between the bight portions of the channel members 12—14, and holding them and their flanges in desiredly spaced and freely slidable relation are anti-friction roller members, which are preferably of the construction best shown in Figures 4 and 5. These will presently be described in greater detail; it suffices for the present to say, however, that they provide freely rolling support for the carriage channel.

Suitable means are provided for securing the carriage channel to the underside of a seat or other object to be supported, such means being shown as comprising a clinch nut 22 carried by the rear extremity of the carriage channel and a pair of suitably tapped apertures extending through the forward extremity of this channel and a rack plate 30 secured to the top thereof (and presently to be described). With these tapped apertures and the clinch nut suitable machine screws 28 cooperate to secure the seat 27 upon the carriage channel.

Near the forward extremity of the track chan-

nel 12 a plurality of latching or detent notches 18 are formed in the edge of one of the flanges 13 and a latching or detent dog 19 is pivotally secured to the upper flange 15 as on the pin 21. 5 A nose or pawl portion 24 of the dog is offset downwardly and extends over the edge of the top flange 18 and thru a slot 23 in the keying guide to enable its engagement with the notches 18. By such selective engagement the seat is securable in desired positions, the dog being yieldably held in engagement with the notches by means of a tension spring 25 stretched between the lug portion 23 carried by the dog and flange 15. Retraction of the dog to free the seat for sliding 10 movement is effected by means of a handle 26 secured to the dog and so projecting forwardly as to position it conveniently near and directly beneath a front corner of the seat.

It will be understood that one such slidable seat supporting assembly or unit as has just been described may be mounted beneath and near each side of the seat, but that only one such unit need be provided with latching means such as that described in the immediately preceding 15 paragraph, since the single latching means carried by one unit is sufficient to lock the seat, although obviously separate latches might be provided if desired, adapted to be worked either by the same handle or separate handles, as desired.

30 In Figure 1 the unit unequipped with latching means is generally designated 35.

Centrally along the upper and lower plate portions of channel members 12-14 are punched a plurality of evenly spaced holes 31-32 adapted 35 to form racks with which the guiding gear portions 42 of the rollers are adapted to engage.

As shown in Figures 4 and 5 each roller may comprise a pair of cylindrically cupped stamped elements 40-41, each having at its open end elements 40-41, each having at its open end 40 similar peripherally spaced flange segments 42 forming gear teeth and cooperating with the teeth of the adjacent cupped unit when the two are assembled in the manner indicated to constitute a gear portion for controlling movement 45 of the roller. The two sections 40-41 are fitted together and over a split spring sleeve 44 by which they are yieldably held, as shown in Figure 4. It will be seen that when these members are so assembled upon the spring sleeve, 50 which is somewhat compressed by the cupped elements, and the assembly inserted in the track and carriage channels 12-14 in the manner shown in Figure 3 and 6, the gear portions formed by the flange serrations are adapted to 55 mesh with the rack apertures 31-32 to positively maintain the rollers in positions and paths of movement within the complementary channels 12-14, while the channels and rack apertures also lock the cupped roller elements in 60 assembled relation and the toothed portions against disalignment. By virtue of the way in which these portions trap the roll elements it will be seen that the inner sleeve 44 might, if desired be omitted, and the sections properly 65 located in any event. In fact the sleeve 44 is chiefly useful in preventing separation of the elements during assembly.

The existence of some slight amount of play or looseness in such adjustable seat supporting devices is as a practical matter unavoidable, 70 since they must work freely and easily, and are ordinarily manufactured in quantities and largely of stampings, as indicated. It has been found as a result that such looseness tends to permit 75 the seat to cock or turn sideways slightly and

sometimes jam, thus seriously interfering with its free movement and the operation of the latching mechanism. This difficulty is particularly noticeable when the seat is attempted to be moved by force applied at one end (as it frequently is). I have shown means adapted to overcome this annoying and troublesome tendency, and positively prevent such cocking of the seat, by providing for equal application of driving force at both ends, no matter from what 10 position the force may be applied, in conjunction with mechanism which also provides a constantly effective lock against tilting.

A cross shaft 50 extends between the opposite units (designated 35-35' in Figure 1) and is 15 provided at each end with a pinion 51 rigidly secured thereto. The ends of the shaft may project beyond the pinions, as shown, to be trunnioned in the vertical flanges of angle brackets 53 which vertical flanges are supported in upstanding position beside the track by horizontal flange portions which project between the track channel 12 and front leg of each unit, where they may be held in any suitable fashion, as by welding. It will be seen that the brackets 53 serve merely 20 as bearing or supporting hangers for the shaft, which is held against undesired end play by the positioning of the flanges directly outside the opposed gears 51, as shown in Figure 6.

Each gear 51 meshes with a rack carried by 25 the appurtenant carriage channel 14. The rack may, as shown, be formed by punching a plurality of slots 55 in desired spaced relation in each rack plate 30 in conformity to teeth of gear 51, as shown in Figures 2 and 6, into which slots the 30 gear teeth fit in meshing relation. By virtue of this arrangement it will be seen that when the seat and so the carriage channel 14 is slid with relation to the supporting channel 12, the movement imparted to one rack 55 turns the shaft 40 50 through gear 51 and so drives the opposed gear and rack, and by such transmitted drive positively moves the opposite end of the seat in like and simultaneous fashion.

The gears 51 being fast upon cross shaft 50, 45 the racks and so the opposite carriages are held in their desired relation at all times, turning or cocking of the seat being thus positively prevented and freedom of movement thereof accordingly insured.

Despite the simplicity of this construction it will be seen to be one of great strength and facile operation. The seat is easily releasable and quickly movable, yet normally rigidly locked in position, and the arrangement of the rollers 40-41 and 55 absence of parts in direct slidable engagement virtually eliminates friction.

While it will be apparent that the illustrated embodiments of my invention herein disclosed are calculated to adequately fulfill the objects and 60 advantages primarily stated it is to be understood that the invention is susceptible to variation, modification and change within the spirit and scope of the subjoined claims.

What I claim is:

1. Supporting means for a seat or the like comprising a pair of spaced substantially parallel track members, a carriage including an inverted channel member movably carried by each track member for travel therealong, said carriage 70 members being adapted to cooperate in supporting a seat, and means connecting said carriage members to insure substantially unitary movement thereof, including a cross shaft rotatably supported by and extending between said track 75

- members in the general plane of said track and carriage members, a pair of gear elements fast on the shaft, and a pair of rack elements, one meshing with each gear, and one secured to and projecting inward from each channel member toward the other, said rack elements comprising plates having perforations therein substantially wider than the thickness of the gears, into which perforations the teeth of the gears extend.
- 5 2. Supporting means for a seat or the like comprising a pair of spaced substantially parallel channel track members, a carriage comprising an inverted channel member movably carried by each track member for travel therealong, said carriage members being adapted to cooperate in
- 10 supporting a seat, and means connecting said carriage members to insure substantially unitary movement thereof, including a cross shaft lying in the general plane of said channel members, bracket means extending laterally from the track 5 members and supporting the shaft for rotation on a relatively fixed axis, a pair of gear elements fast on the shaft, and a rack element comprising a plate carried by each channel member and projecting inwardly therefrom spacedly above the 10 bracket means, each plate having perforations therein wider than the thickness of the gear and meshing with the teeth of one of said gear elements.
